UNITED STATES PATENT OFFICE.

GUSTAV OTTO SCHULZ, OF REVERE, MASSACHUSETTS.

PROCESS OF VACUUM-RECEPTACLE CONSTRUCTION.

1,337,278.

Specification of Letters Patent. Patented Apr. 20, 1920.

Application filed May 23, 1919. Serial No. 300,287.

To all whom it may concern:

Be it known that I, GUSTAV OTTO SCHULZ, a citizen of the United States, and a resident of Revere, in the county of Suffolk and State 5 of Massachusetts, have invented an Improvement in Processes of Vacuum-Receptacle Construction, of which the following description, in connection with the accompanying drawings, is a specification, like characters

10 on the drawings representing like parts.

This application is in part a continuation of my copending application Serial No. 276,811, filed February 13, 1919, now Patent No. 1,307,793, June 24, 1919.

15 This invention relates to the process of vacuum receptacle construction for various purposes, and more particularly for fireless cookers, ice cream cabinets, etc., and also to wall construction of containers, which in the

20 disclosed embodiment of means for practising the invention are typified by sections of walls for vessels adapted to receive a refrigerant and articles to be subjected to refrigerating action.

25 In order that the principle of the invention may be readily understood, I have disclosed in the accompanying drawings certain adaptations of or means for practising my invention, to the use of which, however, 30 my invention is in no wise limited.

In said drawings:

Figure 1 is a horizontal section, and Figs. 2, 3 and 4 are vertical sections taken through a receptacle adapted to be used as a fireless 35 cooker, ice cream cabinet, etc., said receptacles being shown in various stages of construction in accordance with my process;

Figs. 5 and 6 are perspective views showing vacuum receptacles adapted to be used 40 as heat insulating units for walls in different stages of construction; and

Figs. 7 and 8 are perspective views showing vacuum receptacles employed to insulate wooden and concrete walls respectively.

45 I will describe certain embodiments of means for practising my process which may, however, be carried out in any other suitable or approved way.

In Fig. 1 I have shown in horizontal or 50 cross section, and in Fig. 2 in longitudinal section, a hollow core. This core is composed of inner and outer members or walls 1, 1, herein represented as cylindrical, and which are preferably, but not necessarily, 55 formed of wood. Between the walls 1, 1, of the core are supporting or bracing strips 2

that may be of any suitable form, character, number and material. Preferably they are formed of wood. Having constructed a hollow core as shown in Figs. 1 and 2, I envelop 60 the core by a hermetical barrier 3, indicated in Figs. 3 and 4. Such barrier is preferably, but not necessarily, of metal. Attached to or constituting an integral part with the hermetical barrier 3 is a preferably 65 tubular projection 4. In order to facilitate the creating of a vacuum between the members 1 of a hollow core, I provide an opening or passage 5 through the outer wall 1, thus creating communication between the 70 tubular projection 4 and the space between the members 1 of the core. The core having been enveloped by the hermetical barrier 3, a vacuum is created between the members 1 of the core preferably by connecting the 75 tubular projection 4 to a vacuum pump. A vacuum having been established within the core 1, the latter is hermetically sealed by closing the passageway through the projection 4 in any suitable manner, as by means 80 of a cap 6.

In Fig. 4, I have shown a vacuum-insulated cover for the receptacle, indicated generally at 7. The process of constructing a cover is preferably similar to that of constructing the receptacle itself. The hollow core for the cover comprising the members 1^a, 1^a and the supporting or bracing strips 2^a is enveloped by the hermetical barrier 3^a. The upper member 1^a is provided with a 90 tubular projection 4^a, which is in communication with a passage 5^a through the said outer member 1^a. A vacuum is established between said members 1^a and the core is hermetically sealed by closing the passageway 95 5^a in any suitable manner, as by means of a cap 6^a.

In Fig. 5, I have represented a hollow core composed of the members 1^b, 1^b between which are the supporting or bracing strips 100 2^b. The hollow core is provided with an opening 5^b establishing a passageway to the space between the members 1^b.

The core thus constructed having been completed, it is covered by a hermetical barrier, preferably such as indicated at 3^b in Fig. 6. Attached to or constituting an integral part of the hermetical barrier 3^b is a tubular projection 4^b. A vacuum is created within the said core and preferably by 110 connecting the tubular projection 4^b to a vacuum pump, and the core is thus her-

metically sealed by closing the passageway through said projection 4^b. The vacuum is sealed in any suitable manner, as by placing a cap upon said tubular projection.

- 5 Having completed the vacuum receptacle, it may be coated, if desired, with shellac, asphalt or any suitable cementitious material to prevent corrosion and to assist in making the receptacle impervious to air, thus
10 safeguarding against any leakage that may occur on account of the seams or the porosity of the hermetical barrier that envelops the core of the receptacle. The enumerated enveloping materials constitute the preferred
15 adhesive materials for this purpose. My invention is in no wise limited with respect to the size of the core, and any number of additional supports 2^b may be added.

In Fig 7, I have represented a vacuum receptacle employed to insulate a hollow wall, as, for example, the floor and ceiling as well as the side walls of a receptacle of any size, or even of a building. The members 7 of said receptacle may be either the studs of a wall or the joists of a floor or ceiling. The receptacle indicated at 3^b is placed between the said members 8 and is then inclosed by the boards 9, or by any suitable covering, which is usually employed in the construction
25 of walls. Any space that exists between the receptacle 3^b and the covering 9 is preferably filled in with some cementitious material, such as asphalt or pitch, thus eliminating any possible condensation.

30 In Fig. 8, I have represented the vacuum receptacle 3^b embedded in a concrete wall 11. Any desirable method may be used in casting or molding the concrete 11 about the said receptacle 3^b.

40 By enveloping a hollow core, as by a hermetical barrier and then creating a vacuum within the core, the pressure resisting qualities of cheap materials, such as wood, which are not impervious to air, can be utilized,
45 and the use of glass and heavy iron heretofore necessary may be avoided. Consequently, the construction of vacuum receptacles is greatly simplified and made practicable from the commercial point of view.

50 Within the scope of my invention I may employ the following steps in the order enumerated and may form the receptacle or construction shown in Figs. 7 and 8 by such method; that is to say, I may envelop a hollow and preferably relatively rigid core by a hermetical barrier, such as indicated at 3^b. I may then establish a vacuum within said core in any suitable manner. I may then hermetically seal the core, and I may then
55 apply the concrete or cementitious material about said hermetically sealed core. Such process constitutes a different species from that claimed in and broadly covered by my said co-pending application Serial No. 60 276,811, and I desire to claim the same here-

in or in a suitable division of this application.

Having thus described several illustrative embodiments of means whereby my invention may be practised, I desire it to be understood that although specific terms are employed, they are used in a generic and descriptive sense and not for purposes of limitation, the scope of the invention being set forth in the following claims. 75

Claims:

1. That process of vacuum-receptacle construction comprising the following steps; enveloping by a hermetical barrier a hollow core adapted to brace said barrier against atmospheric pressure consequent upon the establishment of a vacuum within said core, establishing a vacuum within said core, then hermetically sealing said core and then enveloping said core or barrier with or applying thereto concrete or cementitious material. 85

2. That process of wall or like construction comprising the following steps; enveloping a hollow, relatively rigid core by a hermetical barrier, then establishing a vacuum within said core, then hermetically sealing said core, and then applying to or enveloping said core and barrier with concrete or cementitious material. 95

3. That process of vacuum-receptacle construction comprising the following steps; enveloping by a hermetical barrier a core having means to brace said barrier against atmospheric pressure consequent upon the establishment of a vacuum within the core, then establishing a vacuum within the core, then hermetically sealing said core, and then applying to said core and barrier or enveloping the same with concrete or cementitious material. 100

4. That process of vacuum receptacle construction comprising the following steps: enveloping by a hermetical barrier a core adapted to brace said barrier against atmospheric pressure consequent upon the establishment of a vacuum within the core, then creating a vacuum within said core, hermetically sealing the core, and then applying to or enveloping the barrier by a coat 110 of adhesive material. 115

5. That process of vacuum receptacle construction comprising the following steps: enveloping by a hermetical barrier a core adapted to brace said barrier against atmospheric pressure consequent upon the establishment of a vacuum within the core, then creating a vacuum within said core, hermetically sealing the core and subsequent to the envelopment of said core by said barrier applying to or enveloping the barrier by a coat of adhesive material. 120 125

In testimony whereof, I have signed my name to this specification.

GUSTAV OTTO SCHULZ.
